UNITED STATES PATENT OFFICE.

GUY CLEMENT HURRELL, OF BLACKHEATH, LONDON, ENGLAND.

EMULSIFICATION APPARATUS.

Application filed November 12, 1927, Serial No. 232,919, and in Great Britain November 13, 1926.

The apparatus herein described is particularly suitable for making small quantities of emulsion and for being operated by hand power, although its application is not limited to small capacities. It is well known that emulsions such as those of oil and water can be effectually made, and crude emulsions homogenized and made stable, by passing the mixture between very closely adjacent smooth 10 surfaces at high velocity and/or high pressure; in the former case the smooth surfaces rotate rapidly with regard to each other as in the case for example of the machine described in my U. S. patent specification 1,496,641.

15 A well known form of apparatus of the pressure kind is that known in commerce as the Gaulin type, in which high pressure pumps force the mixture of oils and water or the imperfect emulsion between a conical 20 valve and a seating of like shape, on to which the valve is forced by means of a powerful spring, the pressure of the liquid causing the valve to lift slightly from its seat. In passing through the narrow space thus formed, 25 the emulsion is made or homogenized.

Both these types of apparatus are known to be effectual, but neither can advantageously be made in small sizes. In the case of the high speed type, owing to the fact that the peripheral velocity is required to be very high, the 30 number of revolutions necessary in a small machine becomes so great as to be objectionable or impractical. The second or pressure type can be made in a small size, but in any 35 form known or previously described it would be disproportionately complicated and expensive to manufacture.

In the drawing accompanying this specification:—

40 Figure 1 is a section through the apparatus in one of its forms.

Figure 2 is a section of an alternative arrangement of the parts.

Figure 3 is a similar view of the preferred 45 form of the apparatus.

In each of the figures like parts are indicated by like figures or letters.

The apparatus forming the subject of this specification functions by means of a simple 50 (preferably single acting) pump, the plunger or piston 1 of which is a deliberately loose fit in the barrel 2, for example one or two thousandths of an inch more or less in the diameter. In practice it has been found that in a 55 pump of about one inch bore the diameter of

the plunger 1 may advantageously be only .0005" (one two-thousandth of an inch) less. To this pump an inlet valve only is provided which is opened on the suction stroke to draw in a charge of the mixture to be emulsified; on 60 the pressure stroke the automatic inlet valve closes and the liquid is forced between the piston 1 and the walls of the barrel 2. It is desirable that the plunger or piston should be of considerable length compared with the bore 65 of the pump, for example one or two diameters, and the operation is found to be improved if one or a number of shallow grooves 4 are formed on the surface of the plunger. The pressure obtained on a small pump of the 70 type described may reach one thousand or several thousand pounds to the square inch.

The pump may be operated in a vertical, horizontal or inclined position, and in the single ended vertical type the plunger 1 may be 75 above the barrel 2 as in Fig. 1 or below as in Fig. 2; and in all cases either the plunger or barrel may move. The inlet valve 3 is preferably a simple spherical metal ball (Figs. 2 and 3) which may close by gravity. The liquid may enter, under the valve, either through a port in the (otherwise closed) end of the barrel (Figs. 1 and 3), or through an axial hole 5 formed in the plunger 1 to which a transverse hole may conveniently communicate, as in Fig. 2. The emulsion, escaping from around the plunger 1 and thence from the barrel 2, may be received by a suitably formed gutter and baffle 7 at or near the open end of the barrel (Fig. 1), or it may be freely 80 discharged and caught in an external receptacle 8 (Fig. 2) especially when the apparatus is in any position except with the mouth of the barrel upwards; but in my preferred form, shown at Fig. 3, I make my pump barrel 2 of increased length sufficient to allow for, firstly at the closed end sufficient for the length of the working part 1^A of the plunger 1 and the travel thereof; secondly, a length equal to the travel and which is opposed by a 85 portion 1^B of the plunger of much reduced diameter; and thirdly of a portion slightly more than the length of the stroke in which moves a portion 1^C of the plunger of maximum diameter as closely as possible fitting the bore. 90 In the wall of the cylinder or barrel 2 is pierced a port or outlet 9 in the centre of the part traversed by the part 1^B of the plunger. It will be seen that the emulsion, leaking past the working part 1^A of the plunger, will exude 95

through this port, the open end of the cylinder being closed by the fitting part 1^c of the plunger. This latter part is intended also to serve as a guide and preserves the alignment of the emulsifying plunger in the barrel.

In the complete apparatus embodying the preferred type of pump or emulsifying unit, I provide a rigid bedplate 10 of metal on which is a pivot 11 for a lever 12, the long end 12^a of which may be gripped by the operator; the short end pivotally engages at 13 with the outer end of the plunger as shown in Fig. 3. The closed end of the cylinder 2 is pivotally anchored at 14 to a lug or anchorage 15 on the base 10 so that the pump may oscillate at least to the extent of the height of the arc traversed by the end of the lever 12. It is clear that the plunger 1 may be anchored to the pivot 14 and the closed end of 20 the cylinder to the lever 12 if so desired without affecting the functioning of the apparatus.

The inlet port may be connected by a flexible or rigid tube 16 as in Figs. 1 and 2 with the supply (such as 16^a Fig. 1) of mixture to be emulsified, but where it is desired to emulsify a definite small quantity of ingredients which have first to be made into a crude or unstable emulsion, such as for example, a 25 substitute dairy cream from milk or milk powder and water and butter with or without other fats, I prefer to fix or to form upon the exterior of the barrel 2 a small vessel, such as 17 in Fig. 3, to the bottom of which the inlet port 5 communicates. In this case the valve is held closed by a spring 18 sufficiently strong to withstand the static pressure of the liquid in the pot, but which will immediately open with the suction stroke of the plunger 30 1; by this method an external cock or valve may be dispensed with on the apparatus. To the pot or vessel may advantageously be fitted a stirring or agitating device such as that shown for example at 21 in Fig. 3. 45 While in the above described preferred form the function of the apparatus is by the direct action of a reciprocating lever, I do not limit myself to this means in the case of the preferred or the alternative arrangements, but may obtain the reciprocating motion 50 of the pump by means of a crank or an eccentric, directly operating on the pump, or by links or rods such as 19 with guides 20 as in Fig. 2, or any known or usual means of 55 obtaining reciprocating motion from any mechanical or other sources of power and movement.

It is contemplated that the combined mixing vessel 17 and barrel 2 may be readily detachable from the base 10, not only for purposes of cleaning but so that the ingredients may be warmed when necessary (as for example in the production of cream as above referred to) by immersing this part of the apparatus in hot water for the requisite time,

and this can be done by making the pin 14 readily removable.

I claim—

1. Means for effecting emulsification of liquid comprising a cylinder with means for delivering such liquid to the cylinder, and a plunger closely fitting within said cylinder said plunger and cylinder movable relatively to one another whereby to force such liquid between the plunger and the cylinder and emulsify it.

2. Means for effecting emulsification of liquid comprising a cylinder with means for delivering such liquid to the cylinder, said means including an automatic valve, and a plunger closely fitting within said cylinder said plunger and cylinder movable relatively to one another whereby to force such liquid between the plunger and the cylinder and emulsify it.

3. Means for effecting emulsification of liquid comprising a cylinder, with means for delivering liquid to the cylinder, a plunger closely fitting within said cylinder, said plunger and cylinder movable relatively to one another in order to force such liquid between the plunger and the cylinder and emulsify it, a mixing vessel mounted upon one of the relatively movable parts and an automatic valve interposed between the mixing vessel and such one of said parts.

4. Means for effecting emulsification of liquid comprising a cylinder having an open and a closed end with means for delivering liquid to the closed end of the cylinder, a plunger within said cylinder, said plunger and cylinder movable relatively to one another in order to force liquid between the plunger and the cylinder, whereby to emulsify such liquid, said plunger constituted by a working portion fitting in the cylinder, a guide portion fitting in said cylinder, said guide portion preventing egress of emulsion from the open end of the said cylinder, and an intermediate portion of reduced diameter forming with said cylinder a chamber to receive emulsified liquid, said cylinder formed with an outlet port adjacent the reduced portion of the plunger, substantially as and for the purpose set forth.

5. Means for effecting emulsification of liquid comprising a cylinder with means for delivering liquid to the cylinder, a plunger closely fitting within said cylinder said plunger and cylinder movable relatively to one another in order to force such liquid between the plunger and the cylinder and emulsify it, a container for the liquid to be emulsified mounted upon one of said relatively movable parts and an automatic valve at the junction of the container and such relatively movable part.

In testimony whereof I have signed my name to this specification.

GUY CLEMENT HURRELL.
